(57) **CLAIM**

The ornamental design for a lamp for a vehicle, as shown and described.

DESCRIPTION

FIG. 1 is a top, right, and front perspective view of a lamp for a vehicle showing my new design;
 FIG. 2 is a top, right, and rear perspective view thereof;
 FIG. 3 is a bottom, left, and rear perspective view thereof;
 FIG. 4 is a front elevational view thereof;
 FIG. 5 is a rear elevational view thereof;
 FIG. 6 is a left side elevational view thereof;
 FIG. 7 is a right side elevational view thereof;
 FIG. 8 is a top plan view thereof; and,
 FIG. 9 is a bottom plan view thereof.

The broken lines in the drawings depict portions of the lamp for a vehicle that form no part of the claimed design.
